(57) **CLAIM**

I claim, the ornamental design for a plate for an electrical dart game machine, as shown and described.

DESCRIPTION

FIG. 1 is a top and front perspective view of a plate for an electrical dart game machine, showing my new design;
FIG. 2 is a front view thereof;
FIG. 3 is a rear view thereof;
FIG. 4 is an enlarged left side view thereof;
FIG. 5 is an enlarged right side view thereof;
FIG. 6 is a top plan view thereof; and,
FIG. 7 is a bottom plan view thereof.

The broken lines showing of a game machine is for environmental purpose only and forms no part of the claimed design. The VSOPHONIX forming part of the claimed design is a registered trademark of HONG International Corp.
